UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

DRILLING APPARATUS

Application filed July 27, 1928. Serial No. 295,814.

My invention relates to drilling apparatus and particularly to a mounting for rock drills.

One object of my invention is to provide an improved drilling apparatus. Another object is to provide improved resilient means for connecting a rock drill to its mounting. Still another object is to provide an improved mounting of simplified construction to which a rock drill of standard construction may be resiliently connected. Other objects and advantages of the invention will hereinafter more fully appear.

In the accompanying drawings I have shown for purposes of illustration one preferred form and two modifications thereof which the invention may assume in practice.

In these drawings,—

Fig. 1 is a side elevational view of a drill mounting and drill with parts broken away to show details of my invention.

Fig. 2 is a transverse sectional view on line 2—2 of Fig. 1.

Fig. 3 is a view similar to Fig. 1, illustrating a modified construction.

Fig. 4 is a vertical section on a line corresponding to line 4—4 of Fig. 3, showing how the construction may be still further modified.

In Fig. 1 of the drawings there is shown a common form of shell mounting for rock drills generally designated 1 having a conical bearing support 2 adapted for connection to a tripod or quarry bar, not shown. A cradle 3 is slidably mounted on the shell 1 by means of guides 4 on the cradle cooperating with guideways 5 on the shell. The cradle is provided with a feed nut boss 6 in which is secured a feed nut 7 having internal threads cooperating with threads on the usual feed screw 8. The feed screw is supported in bearings on the shell, one of which is indicated at 9, the latter being connected to the shell by means of bolts 10 and sleeves 11. The usual handle 12 is shown for manually operating the feed screw to feed the drill and cradle relative to the shell.

A rock drill generally designated 13, which may be, as herein shown, of the com-

mon mounted drifter type, is provided with integral guides 14 slidably received in guideways 15 provided by the cradle as best shown in Fig. 2. Details of construction of the rock drill per se do not enter into the present invention and accordingly will not be further discussed.

In addition to the guides 14, the rock drill cylinder has also a pair of depending lugs 16 and 17, herein shown formed integral therewith which are provided with aligned holes for receiving a bolt 18. A boss 19 projects upwardly from the cradle adjacent the feed nut and between lugs 16 and 17 on the cylinder and is also provided with a central aperture aligned with the apertures in lugs 16, 17 for receiving the bolt 18. Obviously, one or the other of the lugs 16, 17 would be made detachable, or else the boss 19 would be made detachable from the cradle, if the guides 14 are made integral with the drill, to permit assembly. A pair of springs 20 and 21 are interposed between the boss 19 and lugs 16 and 17 for the purpose of providing a resilient connection between the rock drill and the cradle. With this construction it will be observed that the drill is held rigidly against any transverse lateral or vertical movement by means of the guides 14 and guideways 15 which at the same time permit a certain amount of longitudinal movement.

During operation of the hammer drill, when shocks are imparted thereto on account of vibration or any other cause, the springs 20 will cushion such vibration and shock and prevent the same from being transmitted to the cradle and tripod.

The construction shown in Fig. 3 is identical with that shown in Figs. 1 and 2 with the exception that only a single lug 22 is formed on the drill cylinder and a pair of springs 23 and 24 cooperate with the central boss 19 on the cradle and the bolt 18 for cushioning movements of the rock drill in either direction relative to the cradle in the same manner as described in connection with the preferred construction. This construction may possibly have some advantages as regards simplicity and cost of manufacture.

In Fig. 4 there is shown a modification of the guide structure for connecting the drill to the cradle. Instead of forming a pair of guides such as 14 in Fig. 2, the rock drill cylinder has a pair of guideways 25 formed integral therewith which receive a pair of guides 26 on the cradle. In all other respects the construction shown in Fig. 4 is identical with the construction shown and described in Figs. 1 and 2.

As a result of my invention it will be apparent that improved means of very simple and rugged construction have been provided for resiliently connecting the rock drill to a cradle which will materially lessen vibration transmitted to the supporting structure of the drill, thereby tending to increase the stability of the mounting and reduce breakage of the parts.

While I have in this application specifically described one form and two modifications which my invention may assume in practice, it will be understood that this form and modifications of the same have been used for purposes of illustration and that the invention may be modified and embodied in various other forms without departing from its spirit or the scope of the appended claims.

What I claim as new and desire to secure by Letters Patent is:

1. In a drilling apparatus, a shell having a guideway, a cradle having guides slidably mounted in the shell guideway, a percussive rock drill slidably guided in the guides on said cradle, means for feeding said cradle relative to said shell to effect feeding of the rock drill including a feed nut carried by said cradle and a cooperating feed screw on said shell, and resilient shock absorbing connections between said drill and cradle adapted to yield to permit sliding movement of said drill in a rearward direction relative to said cradle.

2. In a drilling apparatus, a shell having a guideway, a cradle having guides slidably mounted in the shell guideway, a percussive rock drill slidably guided in the guides on said cradle, means for feeding said cradle relative to said shell to effect feeding of the rock drill including a feed nut carried by said cradle and a cooperating feed screw on said shell, and resilient double acting shock absorbing connections between said drill and cradle adapted to permit sliding movement of the drill relative to said cradle in opposite directions.

3. In a drilling apparatus, a shell having a guideway, a cradle having guides slidably mounted in the shell guideway, a percussive rock drill slidably guided in the guides on said cradle, means for feeding said cradle relative to said shell to effect feeding of the rock drill including a feed nut carried by said cradle and a cooperating feed screw on

said shell, and resilient double acting shock absorbing connections between said drill and cradle adapted to permit sliding movement of the drill relative to said cradle in opposite directions, and including projecting lugs on 70 said drill and cradle and oppositely acting coiled springs interposed between said lugs.

4. In a drilling apparatus, a shell having a guideway, a cradle having guides slidably mounted in the shell guideway, a percussive 75 rock drill slidably guided in the guides on said cradle, means for feeding said cradle relative to said shell to effect feeding of the rock drill including a feed nut carried by said cradle and a cooperating feed screw on 80 said shell, and resilient double acting shock absorbing connections between said drill and cradle adapted to permit sliding movement of the drill relative to said cradle in opposite directions, and including projecting 85 perforated lugs on said drill and cradle, a bolt extending through the perforations in the lugs and oppositely acting coiled springs encircling said bolt and interposed between 90 said lugs.

5. In a drilling apparatus, a shell having a guideway, a cradle having guides slidably mounted in the shell guideway, a percussive rock drill slidably guided in the guides on 95 said cradle, means for feeding said cradle relative to said shell to effect feeding of the rock drill including a feed nut carried by said cradle and a cooperating feed screw on said shell, and resilient shock absorbing connections between said drill and cradle adapted to yield to permit sliding movement of 100 said drill in a rearward direction relative to said cradle and including projecting lugs respectively carried by said drill and cradle and a spring yieldable to permit relative 105 movement between said lugs.

6. In a drilling apparatus, a shell having a guideway, a cradle having guides slidably mounted in the shell guideway, a percussive 110 rock drill slidably guided in the guides on said cradle, means for feeding said cradle relative to said shell to effect feeding of the rock drill including a feed nut carried by said cradle and a cooperating feed screw on said shell, and resilient shock absorbing 115 connections between said drill and cradle adapted to yield to permit sliding movement of said drill in a rearward direction relative to said cradle and including projecting lugs respectively carried by said cradle and drill, 120 a bolt extending between said lugs, and a spring surrounding said bolt to the rear of the lug on said drill.

7. In a drilling apparatus, a shell having a guideway, a cradle having guides slidably 125 mounted in the shell guideway, a percussive rock drill slidably guided in the guides on said cradle, means for feeding said cradle relative to said shell to effect feeding of the rock drill including a feed nut carried by 130

5 said cradle and a cooperating feed screw on said shell, and resilient shock absorbing connections between said drill and cradle adapted to yield to permit sliding movement of
10 5 said drill in a rearward direction relative to said cradle and including projecting lugs respectively carried by said cradle and drill, the lug on the latter being to the rear of the lug on the former, a bolt extending between said lugs, and a spring surrounding said bolt and to the rear of the lug carried by said drill.

15 8. In a drilling apparatus, a shell having a guideway, a cradle having guides slidably mounted in the shell guideway, a percussive rock drill slidably guided in the guides on said cradle, means for feeding said cradle relative to said shell to effect feeding of the rock drill including a feed nut carried by
20 20 said cradle and a cooperating feed screw on said shell, and resilient double acting shock absorbing connections between said drill and cradle adapted to permit sliding movement of the drill relative to said cradle in opposite directions and including projecting lugs respectively carried by said cradle and drill, oppositely acting coiled springs arranged at opposite sides of said last mentioned lug, and a bolt extending through said springs and
25 30 lugs.

In testimony whereof I affix my signature.
ELMER G. GARTIN.
